WILLIAM RODERICK BARCLAY AND FRED RICKS, OF LEICESTER, ENGLAND, ASSIGNEES
TO UNITED SHOE MACHINERY CORPORATION, OF PATERSON, NEW JERSEY, A COR-
PORATION OF NEW JERSEY

HEEL SEAT FITTING MACHINE

Application filed May 10, 1932, Serial No. 276,580, and in Great Britain October 10, 1927.

This invention relates to heel-seat fitting machines, and is herein shown as embodied in a machine for shaping or blending the heel-seat of a sole for the reception of a wooden 5 Louis heel. In this process, it is desired to narrow and reduce the heel-seat portion of the sole so that it will fit within the cup of the heel and to form at each side of the reduced portion a tapering tab which, in the 10 finished shoe, is curved downwardly against the breast surface of the heel and secured thereto at its breast corners. More specifically, the present invention relates to machines for forming such tabs and contemplates the 15 provision of a machine of improved design for this purpose.

In machines as heretofore constructed, wherein the portion of the sole area constituting the tabs is matrix-shaped preliminarily 20 to the cutting operation, the knife has traveled in a heelward direction toward the thin end of the tab. Such a machine is disclosed, for example, in United States Letters Patent No. 1,783,212, granted December 2, 1930, on our 25 application. As distinguished from that type of machine, the present invention contemplates a construction characterized by members for clamping the material of the sole adjacent to the root of the heel seat portion to form bulged portions of the sole and cutting means movable in a toeward direction arranged to enter the bulged portions to form 30 tabs at the heel seat portion of the sole. A machine organized in this manner possesses 35 advantages in compactness of construction and accuracy of operation which are of importance from the practical standpoint.

The invention also contemplates, as an important feature, an improved matrix-shaping 40 element, comprising a die having spaced matrix surfaces, each with a portion disposed in the path of a cutting knife and thus determining the point of emergence of the knife from the sole at the thick end of the tab. The 45 die is herein shown as pivotally mounted and arranged to be displaced by the sole operated on in accordance with its thickness and accurately to shape to the desired configuration the portions of the sole from which the tabs 50 are cut.

To insure a clean cut entrance of the knife at the surface of the sole, it is proposed, in accordance with another feature of the invention, to subject a portion of the sole to compression between gripping members, one 55 of which has a defined edge. The gripping members are so shaped and located as to release the compression of the sole and permit the material thereof to bulge in an abrupt shoulder past such defined edge. The knife 60 thereupon enters the sole at a favorable angle through the surface included in the shoulder.

The invention also includes within its scope the novel method of treating a sole herein shown as carried out by cooperating gripping 65 members and knife organized in the manner set forth.

These and other features of the invention will be best understood and appreciated from the following description of a preferred embodiment thereof, selected for purposes of 70 illustration and shown in the accompanying drawings, in which

Fig. 1 is a plan view of the machine with certain parts broken away; 75

Fig. 2 is a view in side elevation, partly in section, of the sole-shaping members and knife with the sole positioned for the cutting operation;

Fig. 3 is a view in perspective of the operating parts of the machine; 80

Fig. 4 is a view in side elevation, partly in section; and

Fig. 5 is a view in perspective of the rear end of a sole after it has been operated upon 85 by the illustrated machine.

Before proceeding to a description of the machine, it will be convenient to refer to Fig. 5, from an inspection of which the condition of the sole coming to the machine and the operation performed upon it by the machine will be apparent. The first step in preparing the heel-seat of the sole 100 for the reception of a Louis heel consists in splitting a flap or leaf 102 from the grain side thereof. This flap extends for the full width of the heel-seat and longitudinally to a point forward of the breast line. In the finished shoe, it is adapted to be laid against the breast surface of the heel and to form a smooth con- 100

tinuous surface merging into the shank surface of the sole. The heel-seat end of the sole beneath the flap 102 is then narrowed or reduced to form a tongue 104, with an edge 5 surface tapering away from the flesh side of the sole and toward the split surface shown as exposed in Fig. 5. The tongue is shaped by cutting a horseshoe-shaped trimming 106 which is not completely severed from the sole 10 but remains attached to it adjacent to the root of the tongue 104. The formation of the flap 102 and the tongue 104 on the sole may be referred to as previously fitting the sole and are carried out by any commercial machine 15 available for the purpose and the sole in the condition just described comes to the machine of our invention for further treatment.

The tapered tabs 108 are formed of the material of the sole at the root of the horseshoe-shaped trimming 106 by cuts 107 entering the sole at its split surface in slightly convergent and oppositely disposed relation and extending obliquely in a toe-ward direction, emerging from the lower flesh surface of the sole, as 20 shown in Fig. 5, in substantial alignment with each other. As will be apparent, it is important that the tabs 108 should be located accurately in alignment with each other widthwise of the sole and it is also desirable 25 that they should taper inwardly from their outer edge and lengthwise as well as flare somewhat toward their thin end portions, in order to lie more smoothly against and conform to the shape of the Louis heel breast. 30 In Fig. 5, the tab-forming cuts 107 are shown as not completely severing the horseshoe-shaped trimming 106 but leaving a small amount of material in each corner of the base of the tongue 104. It will be apparent 35 that by shifting the cuts 107 slightly, the trimming 106 could be completely severed and removed from the sole. The machine herein shown is adapted to sever the trimming 106 completely if desired, or to leave it lightly 40 attached, in accordance with the requirements of the work in hand.

It will be assumed that the sole, before it comes to the present machine, has been split to form the breast flap 102 and that it has 45 been operated upon by such a machine as is described in United States Letters Patent No. 1,757,219, granted May 6, 1930, on the application of Ricks & Richards, to form the reduced heel-seat portion or tongue.

The illustrated machine comprises a base 50 10, adapted to be affixed to a bench or column in such a position that the operator can operate the machine and conveniently see the work while in process, the front of the machine being toward the left in the figures of the drawings.

The base 10 is provided with a base plate 55 12, having its front edge 14 extending transversely across the machine and beveled on its under side to form a thin edge. Arranged

to reciprocate longitudinally of the machine above the base plate 12 is a knife slide 16, connected through a link 18 to an actuating handle 20 disposed within convenient reach of the operator. The rear movement of the knife slide 16 is limited by a stop screw 22, mounted in an arm projecting rearwardly from the frame. The knife slide 16 carries a knife 24, sharpened by a single bevel on its lower side and arranged to travel upon and in contact with the plane upper surface of the base plate 16. The knife is rigidly secured in place upon the knife slide 16 by a clamping plate 26 and bolts 28, which are threaded into the knife slide.

Mounted in the lower front part of the base 10 is a plunger 30, which is actuated vertically by a treadle through a lever 32 and lever rod 34. The uppermost position of the plunger 30 is adjustably determined by a stop screw 36, set in the frame of the machine and arranged to engage the rear end of the operating lever 32 when the treadle is depressed to the limit.

The plunger 30 carries at its upper end a die member 38, which is generally forked or U-shaped and pivotally mounted upon a horizontal pin 40, carried by a lug 42 located between the arms of the U-shaped member on top of the plunger 30. The die member 38 is arranged to rock freely and is normally forced upwardly at its rear side by a compression spring 44 into a position in which its rear ends are somewhat higher than its front portion. The die member 38 carries at each side of the lug 42 and disposed upon its side arms a pair of hardened die plates or matrix members 46. The front end of each of these die plates is curved concentrically about the axis of the pivot pin 40, so that the vertical location of these surfaces shall not be affected by the angular movement of the die member 38 about its pivot pin.

The vertical movement of the plunger 30 is so adjusted that when the plunger is moved upwardly into operative position, the surface of the die plates 46 above the pivot pin 40 lies in the plane of the top surface of the base plate 12 and coincides with the plane of movement of the knife edge. The highest portions of these surfaces are arranged in a line parallel with the front edge of the base plate 12 and spaced in front thereof by a distance equal to the length of the tab that is to be formed in the sole.

Each die plate 46 extends rearwardly so as to come as far back but no further back than the front edge 14 of the base plate 12. The rearmost portions of the die plates 46, under the actuation of the compression spring 44, are adapted when the plunger 30 is raised to engage and firmly grip areas in the sole located in the forward end of the sides of the horseshoe-shaped trimming 106. These areas are firmly pressed against the under side of

the beveled portion of the base plate 12 and the yielding movement of the die member 38 depends upon the thickness of the portions of the sole engaged between the die plates 46 and the base plate 12. The surface of the die plates 46 is shaped to impart the desired contour to the tabs. As herein shown, these surfaces are concave or sloped so as to matrix-shape the material of the sole, in such manner as to cut the tabs with a thin longitudinal inner edge and tapering uniformly to a thick outer edge. The die plates 46 may be said to form effective matrix surfaces extending longitudinally and transversely of the path 15 of the knife at an angle to the path, the two plates as illustrated (Fig. 3) being inclined to each other.

It will be apparent that the position of the tabs longitudinally of the sole is determined 20 by the position in which the legs of the horse-shoe-shaped trimming are gripped between the die plates 46 and the base plate 12. In order to gauge the sole correctly in presenting it to the machine, a thin forwardly-projecting gauge blade 50 is mounted upon the base plate 12. This is adapted to bear at the junction of the breast flap and the body of the sole as the sole is pushed rearwardly into the machine with the flap uppermost. The 25 blade 50 is located slightly above the level of the base plate 12, so that the under surface of the sole below the root of the flap will be located substantially in the plane of the top surface of the base plate 12. The gauge blade 30 50 is adjustable forwardly and rearwardly in the machine through a screw and slot connection 52 with the base plate 12, in order to accommodate soles split to different extents or to vary the location of the tabs. Preferably, the arrangement of the parts is such 35 that the knife 24 will run out of the sole on the flesh surface thereof on lines extending transversely somewhat forward of the root line of the tongue 104. The knife 24 is provided with a centrally located recess 25, so 40 that in its reciprocation it will clear the gauge blade 50.

It is desirable that the legs of the horse-shoe-shaped trimming 106, after they have 45 been gripped between the die plates 46 and the base plate 12, should be pressed down into intimate contact with the die or matrix surfaces before the knife 24 begins to operate. For this purpose, a presser roll is associated 50 with each die member and arranged to be advanced into operative position simultaneously with the movement of the knife and in advance thereof. The knife slide 16 carries at each edge an upstanding bracket 60 upon 55 which is pivoted, on an eccentric pin 62, a rocking bar 64 extending forwardly and rearwardly of the machine and carrying a cam roll 66 at its rear end. A stationary cam plate 68, secured to the frame of the machine 60 is arranged to swing the bar 64 as the knife

slide is moved forwardly in the machine. The bar 64 carries at its forward end a presser illustrated as a roll 70 and this is normally elevated by a compression spring 72 which acts always to swing the rear end of the bar 64 downwardly and hold the cam roll 70 in contact with the stationary cam 68.

The front end of the bar 64 is provided with a boss 74, into which is screwed a hollow rod 76 having at its upper end a knurled head 78, by the turning of which the vertical position of the rod 76 can be adjusted. Mounted within the hollow rod 76 is a plunger 80, the upper end of which is reduced to pass freely through a small hole in the upper end of the rod 76 and is provided with a threaded nut 82. A spring within the rod 76 normally presses the plunger downwardly until the nut 82 engages with the knurled head 78. This arrangement permits the plunger 80 to yield upwardly and, at the same time, by turning the knurled head 78, the plunger may be bodily adjusted without affecting its tension.

The lower end of the plunger 80 is provided with a head 84 which carries the horizontal axis for the presser roll 70. The axis of the roll is disposed parallel to the knife edge and is located laterally so as to position the roll 70 directly above one leg of the 95 horseshoe-shaped trimming. If, as preferred, the die plates 46 are formed to provide tabs tapering laterally of the sole, the presser rolls 70 may be shaped with a corresponding taper. The stationary cam 68 is so shaped that the presser rolls 70 will be moved down into contact with the work just before the cutting edge of the knife reaches the latter. It will be understood that the rollers run upon the flap 102 and act upon the 100 legs of the trimming 104 through the medium of the latter.

In order that the knife 24 shall enter the work in a clean, well-defined cut immediately 110 in front of the front edge 14 of the base plate 12 and in order to counteract any tendency of the knife to displace the work rather than at once entering it, the die plates 46 are so shaped as to bulge the work upwardly at the front edge 14 of the base plate. This has the 115 effect of increasing locally the angle which the surface of the work makes with the knife and thus gives the latter a better chance of entering the work. We have found that an upward bulge of five to ten thousandths of an inch is sufficient to insure the desired results.

The method of treating soles in the manner above outlined, as already pointed out, is believed to be broadly new. The plate 12 125 and the die plates 46 constitute cooperating sole gripping members which subject the sole to compression over an area adjacent to the edge 14 of the plate 12. The edge 14 of the plate is defined to impart the desired con- 130

tour to the material of the sole pressed against it. At the edge 14, the compression of the sole is released and consequently the material of the sole bulges upwardly in a shallow but abrupt shoulder contiguous to the edge 14 and coextensive therewith. The knife 24, moving at an acute angle to the general plane of the sole surface, encounters this shoulder and enters the sole through the surface included in the shoulder and substantially at the base thereof.

The operation of the machine will be apparent from the foregoing description but for convenience may be summarized as follows. A sole is presented to the machine with the grain side uppermost and the heel end toward the rear. The flap 102 is positioned to lie above the base plate and the knife and gauge blade 50. The horseshoe-shaped trimming 106 is positioned above the die plates 46 and underneath the base plate 12, and the tongue 104 is either turned downwardly in front of the die member or passed into the space between the die plates 46. The treadle 25 is then depressed so that the legs of the horseshoe-shaped trimming 106 are gripped between the rear portions of the die plates 46 and the front edge 14 of the base plate. Upon further depression of the treadle, the die member is rocked about the pivot pin 40 until the die plates assume a rearwardly inclined position and their surfaces slope downwardly from the higher concentric portion thereof. The knife 24 is then moved forwardly through the handle 20 by the operator, the two presser rolls travelling slightly in advance thereof and cooperating with the die to bend or twist the trimming at the bulged portion thereof transversely of the sole. The sole being positioned as above explained, the knife 24 enters the legs of the horseshoe-shaped trimming as they are bulged upwardly in front of the edge 14 and cuts progressively obliquely in a toe-ward direction through the material of the sole, emerging at the concentric surfaces of the die plates 46, which act to some extent as shear blades for the knife. In this operation, the horseshoe-shaped trimming 106 is severed except for a slight connection at each side of the tongue, and tabs are formed at the root of the tongue each having a long uniform bevel longitudinally of the sole and a thin longitudinal inner edge tapering uniformly widthwise of the tab to a thick outer edge, the cutting action having proceeded from the thinner rear edge of the tab toward its thicker base or root. If it is desired to level the heel-seat of the shoe while the horseshoe-shaped trimming 106 is still attached to the sole, the tab-forming cuts are so disposed as to leave the connection already mentioned. If it is preferred that the trimming should be completely severed, the location of the tab-form-

ing cuts can be shifted to affect the desired results.

In some of the appended claims, for convenience of expression, the tab-cutting means is defined as moving with respect to the sole support. It will be understood, however, that it is in various aspects of the invention of only secondary consequence which of the two elements actually moves, it being relative movement of the two that is essential.

Having thus described our invention, what we claim as new and desire to secure by Letters Patent is:

1. A heel-seat fitting machine, having in combination cooperating members for engaging the opposite surfaces of a sole having a reduced heel-seat portion, constructed and arranged to clamp the material of the sole adjacent to the root of the heel-seat portion and to form bulged portions in the sole, a presser arranged to engage the bulged portions for cooperating with one of said members in compressing the sole, and tab cutting knives movable in a toe-ward direction arranged to enter the bulged portions to form tabs at the heel-seat portion of the sole.

2. A heel-seat fitting machine, having in combination a knife movable in a predetermined path, and dies for engaging the lateral portions of a sole having a reduced heel-seat portion, each of said dies having a curved portion arranged to be positioned tangentially to the path of said knife and an effective surface extending therefrom at an angle to the path, both longitudinally and transversely of the path, for supporting a sole and for cooperating with the knife to form a tab upon the sole.

3. A heel-seat fitting machine, having in combination a tab cutting knife movable in a predetermined path, and a die mounted for angular movement about a transverse axis and having the highest point in its surface disposed in the path of the knife.

4. A heel-seat fitting machine, having in combination a tab cutting knife movable in a rectilinear path, and a pair of dies having their effective surfaces inclined to the path of the knife and to each other and having portions extending into the path of the knife.

5. A heel-seat fitting machine, having in combination a knife movable in a predetermined path, and sole locating means including a plunger movable transversely with respect to the path of the knife and carrying a pivotally mounted die member.

6. A heel-seat fitting machine, having in combination a knife movable in a predetermined path, and sole locating means including a plunger movable toward the path of the knife and carrying a die pivotally supported at one edge and arranged to assume an inclined position with reference to the path of the knife by pressure of a sole thereon.

7. A heel-seat fitting machine, having in

combination a knife movable in a predetermined path, a pivotally supported die for locating a sole in the path of the knife, and presser means movable with the knife and 5 acting through the sole to establish the operative angular position of the die.

8. A heel-seat fitting machine, having in combination a knife movable in a predetermined path, a die movable bodily toward the 10 path of the knife and also angularly about a transverse axis, and yielding means for opposing such angular movement.

9. A heel-seat fitting machine, having in combination a tab cutting knife movable in 15 a predetermined path, and solelocating means including a support for engaging one surface of a sole, and a die movable to engage the other surface of the sole and being pivotally mounted and yieldingly positioned to 20 engage the sole first adjacent to the support and then to assume a different angular position with reference to the path of the knife.

10. A heel-seat fitting machine, having in combination a support having a sole locating 25 edge, a knife movable over the surface of the support, and a die plate the lateral portions of which are raised relatively to the central portions thereof constructed and arranged to press a sole obliquely against the edge of the 30 support and being shaped to bulge the work upwardly at said edge and to cause the sole to bend widthwise thereof into the path of the knife to a shape corresponding to the shape of the die plate.

35. 11. A heel-seat fitting machine, having in combination a forked sole support, a sole locating gauge acting between the branches of the support, and a tab cutting knife cooperating with said support.

40. 12. A heel-seat fitting machine, having in combination means for supporting a sole at separate areas at the sides of its heel-seat, a sole locating gauge acting between the supported areas of the sole, and tab cutting 45 knives arranged to act upon the supported portions of the heel-seat.

13. A heel-seat fitting machine, having in combination means for supporting and distorting a sole to form a bulge therein, a gauge 50 arranged to position the sole relatively to said means, and a knife movable over the gauge and having a recess formed in its edge to permit the passage of the gauge while the knife acts upon the bulged portion of the 55 sole to form tabs thereon.

14. A heel-seat fitting machine, having in combination a sole support, a knife mounted for sliding movement relatively to the support and constructed and arranged to sever 60 from the sole portions on opposite sides of a reduced heel-seat portion of the sole to form tabs at opposite sides of the reduced heel-seat portion, a presser roll mounted for movement with said knife, and means for automatically operating the presser roll toward

the knife to engage the sole ahead of the knife as the knife is advanced for the cutting operation.

15. A heel-seat fitting machine, having in combination a sole support, a knife mounted for sliding movement relatively to the support and constructed and arranged to sever from the sole portions on opposite sides of a reduced heel-seat portion of the sole to form tabs at opposite sides of the reduced heel-seat portion, a presser lever arranged for movement with the knife, a presser roll carried by the lever in advance of the knife, and a cam for swinging the lever to force the presser roll upon the work as the knife is advanced for 75 the cutting operation.

16. A heel-seat fitting machine, having in combination a sole support having spaced die surfaces, a single knife movable in a path adjacent to said surfaces to cut a pair of tabs simultaneously in cooperation therewith, and independently mounted presser rolls movable to conform separate sole areas to said die surfaces in advance of the cutting operation.

17. A heel-seat fitting machine, having in combination a support having a die surface, means for separating the flap of a split sole from the body thereof when the sole is presented to said support, and a presser roll movable first in a path above the flap and then 90 into engagement therewith to press the sole into conformity with the die surface.

18. A heel-seat fitting machine, having in combination a die member, a thin plate adjacent thereto for separating the flap of a split sole from the body thereof when the sole is presented to the die member, a presser roll normally located above said thin plate, means for moving said presser roll downwardly to press the sole against the die member, and a 100 knife movable along the surface of said plate to enter the sole at the edge thereof.

19. A heel-seat fitting machine, having in combination a thin edge plate arranged to engage a sole with one of its surfaces, a knife movable upon the other surface of the plate and passing off of the edge thereof, and pivotally mounted means acting upon the sole to bulge the material thereof past the edge of the plate and into the path of said knife.

20. A heel-seat fitting machine, having in combination a plate having a plane surface and an intersecting beveled surface, a knife movable upon the plane surface of the plate, and means mounted for rectilinear and pivotal movement relatively to the plate for forcing a sole against said beveled surface to bulge the material thereof past the edge of the plate and beyond its plane surface to form tabs on the sole.

21. A heel-seat fitting machine, having in combination a knife guiding plate, a knife movable thereon, a pivotally mounted die member movable to engage one surface of a sole adjacent to the edge of said plate to ma-

- trix-shape a portion of the sole and to bulge the material of the sole beyond the edge of the plate and into the path of the knife movable thereon, and means arranged to press the bulged portion of the sole against the die during the movement of the knife.
22. A heel-seat fitting machine, having in combination sole distorting means, including a member having a defined edge, for subjecting one portion of a sole to compression and releasing the sole from pressure beyond said edge so that the material of the sole may bulge past the edge, and a knife movable across said edge and arranged to enter the distorted sole in the shoulder of the bulge to produce a tab which is gradually tapered across its width and along its length.
23. A heel-seat fitting machine, having in combination cooperating sole-gripping members one of which has a defined edge and the other of which has a sole supporting die mounted for pivotal movement relatively to the said edge, said members being relatively movable to subject a portion of a sole to compression and so shaped as to release it from pressure beyond said edge, permitting the material of the sole to bulge past the edge, and a knife movable substantially at right angles to the direction of pressure to enter the sole along the line of the bulge.
24. A heel-seat fitting machine, having in combination means for gripping a sole to subject a portion thereof to compression, said means including a defined edge and also a sole supporting die mounted for rectilinear and pivotal movement relatively to said edge to cause a bulge on the portion of the sole supported on the die, and a knife movable at an acute angle to the surface of the sole and arranged to enter the same at its bulged portion to form tabs upon the sole.
25. The method of producing tapered tabs at the heel-seat portion of a sole which consists in matrix-shaping a horseshoe-shaped trimming formed upon a previously fitted sole longitudinally of the sole to form a bulge intermediate the length of the trimming, twisting the trimming at the bulged portion transversely of the sole, and then causing a knife to enter the trimming at a line defined by the bulge to produce a matrix-shaped tab.
26. That improvement in methods of producing tapered tabs at the heel-seat portion of a sole which consists in distorting a horseshoe-shaped trimming formed upon the previously fitted sole longitudinally of the sole to produce a bulge intermediate the length of the trimming, twisting the sides of the horseshoe-shaped trimming at the bulged portion transversely of the sole, and cutting through said bulged portion along a predetermined path to product tabs which are tapered gradually across their width and lengthwise thereof.
27. The method of producing tapered tabs at the heel-seat portion of a sole which consists in bulging the trimming formed upon a previously fitted sole longitudinally of the sole to form a bulge intermediate the length of the trimming, bending the trimming at the bulged portion transversely of the sole, and then causing a knife to enter the trimming at a line defined by the bulge to form a tab.
28. That method of producing tapered tabs at the heel-seat portion of a sole which consists in distorting a trimming formed upon a previously fitted shoe longitudinally of the sole to produce a bulge intermediate the length of the trimming by engaging opposite faces of the trimming, bending the trimming at the bulged portion transversely of the sole, and cutting through said bulged portion along a predetermined path to produce tabs which are gradually tapered across their width and lengthwise thereof.
29. A heel-seat fitting machine having, in combination, a knife movable in a predetermined path, means for distorting a trimming formed upon a previously fitted sole longitudinally and transversely of the sole to produce bulges intermediate the length of the trimming, and means for moving the knife to cooperate with said means in severing the trimming at its bulged portions to form upon the sole tabs which are gradually tapered across their width and lengthwise thereof.
30. A heel-seat fitting machine having, in combination, means for distorting a trimming formed upon a previously fitted sole longitudinally and transversely of the sole to produce a bulge intermediate the length of the trimming, and a knife constructed and arranged to cooperate with said means in severing the trimming at its bulged portion to form upon the sole a tab which is gradually tapered across its entire width and lengthwise thereof.
31. A heel-seat fitting machine having, in combination, means for distorting a trimming formed upon a previously fitted sole longitudinally and transversely of the sole to produce a bulge intermediate the length of the trimming, said means including a member for engaging one surface of the sole and a die for engaging the opposite surface of the sole, and means for severing the trimming at the bulged portion thereof to form at the heel-seat portion of the sole a tab tapered across its entire width and lengthwise thereof.
32. A heel-seat fitting machine having, in combination, a member for engaging one surface of a sole, a die arranged to engage the opposite surface of the sole, said die and member being arranged for relative movement for distorting a trimming formed upon a previously fitted sole transversely and longitudinally of the sole to produce a bulge intermediate the length of the trimming, and

5 a knife constructed and arranged to cooperate with the die in severing the trimming at its bulged portion to form upon the sole a tab which is gradually tapered across its width and lengthwise thereof.

10 33. A heel-seat fitting machine having, in combination, a knife movable in a predetermined path, a member arranged to engage a surface of a sole, a die arranged to engage the opposite surface of the sole and having a curved sole supporting portion arranged tangentially of the path of the knife and an effective surface extending longitudinally and transversely of the path of the knife at 15 an angle to said path for cooperating with the member to distort a trimming formed upon a previously fitted sole longitudinally and transversely of the sole to produce a bulge intermediate the length of the trimming, and means for moving the knife to sever the sole at the bulged portion to form upon the sole a tab which is gradually tapered across its width and lengthwise thereof.

20 34. A heel-seat fitting machine having, in combination, a knife movable in a predetermined path, a member for engaging a surface of the sole, a die mounted for pivotal and rectilinear movement relatively to the member and arranged to engage the opposite surface of the sole, the member and the die being constructed and arranged to distort a horseshoe-shaped trimming formed upon a previously fitted sole longitudinally of the sole to produce bulges on opposite sides of the trimming, and means for moving the knife to cooperate with the die in severing the trimming at the bulged portions to form upon the sole tabs which are tapered across their width and lengthwise thereof.

25 35. A heel-seat fitting machine having, in combination, a knife movable in a predetermined path, a die plate having a curved portion arranged to be positioned substantially tangentially of said path and having a sole-supporting surface extending longitudinally and transversely of the path and inclined at an angle to said path for supporting a sole, a roll constructed and arranged to press the sole supported upon the die plate against the plate and to cooperate with the die plate for 30 distorting the sole widthwise thereof as the knife moves in said path past the distorted sole to form tabs upon the sole.

35 36. A heel-seat fitting machine having, in combination, a member provided with a flat surface and terminating in a thin edge, a knife movable over said surface, die plates positioned near each other and having sole-supporting surfaces inclined to each other, said plates being constructed and arranged to press a sole obliquely against the edge of the member to cooperate with the edge for causing the sole to bend widthwise thereof into the path of the knife, and a roll having 40 a sole-engaging surface corresponding in

shape to the supporting surfaces of each die plate to insure that the sole is bent widthwise thereof into the path of the knife to a degree determined by the shape of the supporting surfaces.

70 In testimony whereof we have signed our names to this specification.
